(57) **CLAIM**

The ornamental design for a diverter plate, as shown and described.

DESCRIPTION

FIG. 1 is a front view of the diverter plate in the present invention.

FIG. 2 is a rear view thereof.

FIG. 3 is a top view thereof.

FIG. 4 is a bottom view thereof.

FIG. 5 is a right side view thereof.

FIG. 6 is a left side view thereof.

FIG. 7 is a front upper side perspective view thereof; and, FIG. 8 is a rear lower side perspective view thereof.

The view labels used herein to denote front, back, top, bottom and side views are for convenience only and should not be interpreted as limiting the orientation of the diverter plate.

The broken lines in the Figures are for illustrative purposes only, and form no part of the claimed design.
